UNITED STATES PATENT OFFICE.

BENJAMIN F. FLINT, OF CINCINNATI, OHIO.

TIME-LOCK.

SPECIFICATION forming part of Letters Patent No. 276,383, dated April 24, 1883.

Application filed October 7, 1882. (Model.)

To all whom it may concern:

Be it known that I, BENJAMIN F. FLINT, of Cincinnati, in the county of Hamilton and State of Ohio, have invented certain Improvements in Time-Locks, Time Attachments, and Time Mechanism, of which the following is a specification.

This invention relates to that system of locking apparatus wherein a time-movement is arranged to operate in connection with a permutation or other non-time lock for the purpose of preventing the retraction of the locking bolts; and it relates more particularly to that class of combined mechanisms wherein provision is made for disconnecting the time mechanism from the non-time lock at will, and for automatically re-establishing the connection before the locking-bolt can be retracted in case the time mechanism should be in motion at the time the disconnection is effected.

My apparatus embraces a combination of the systems represented in the patents granted to H. Gross, February 8, 1876, No. 173,121; to B. F. Flint, September 28, 1880, No. 232,604, and to Kook and Hall, February 25, 1879, No. 212,610, arranged in a peculiar relation to each other in connection with various improved details and devices of my own construction.

Referring to the accompanying drawings, Figure 1 represents a face view of a safe-door and its train of bolt-work with my improved locking mechanism applied thereto, the parts being shown in a locked position. Fig. 2 is a similar view with the parts shown with the time-movement disconnected from the locking devices. Fig. 3 is an edge or side view of the time-movement. Fig. 4 is a detail view illustrating the relation of the disconnecting devices to the timer. Fig. 5 is a perspective view of the angle-bar employed in the combination-lock as a means of disconnecting the timer. Fig. 6 is a rear face view of the trigger or finger of the time-movement. Fig. 7 is a view illustrating the tripping or throw-off mechanism as used in connection with a duplex time-movement to automatically reconnect the same with the locking devices.

Referring to the drawings, A represents the safe-door; B, the bar by which the train-bolts are connected and operated; C, the time-movement; D, the permutation or non-time lock,

and E a lever upon which the time-movement and the lock are both arranged to act for the purpose of retaining the bolts in a locked position.

The above-named parts are of substantially the ordinary construction and arrangement.

When the bolts are in a locked position their retraction is prevented by means of a block or stud, a, formed upon one end of the lever E, and bearing solidly between the bolt-operating bar B and a rigid stud, b, on the safe-door, as shown in Figs. 1 and 2.

The unlocking of the bolt mechanism is effected by dropping the end of lever E so as to remove its stud a from behind the stump of bar B; hence it is the function of both the combination-lock and the time-movement to prevent the forward end of the lever E from falling. The combination-lock D has its bolt arranged, as usual, to lie beneath a roller on the end of lever E, to hold the same in an elevated position while the timer engages or locks over its rear end in the manner represented in Fig. 1.

The time-movement and its trigger F are constructed and operated in substantially the same manner as that described in the patent to Henry Gross, hereinbefore named, the trigger being pivoted to the frame of the time-movement and thrown into action by a spring when released by one of the hands of the timer. The time-movement is provided with an adjustable revolving hand, G, which acts at the end of the predetermined period upon a shoulder of the trigger F to unlock the latter from the lever E. A dog or latch, H; is also arranged, as in the Gross patent, for the purpose of holding the trigger out of action for such a length of time as may be desired, a second adjustable hand, I, being applied to the time-movement to act upon the dog H and throw the trigger F into action automatically in the same manner as in the Gross patent. In the event of a stoppage of the time-movement before the release of the trigger F thereby it would manifestly be impossible to gain access to the safe without resorting to violence. To avoid this difficulty I provide, as in the patents to Kook and Hall, a connection between the time-movement and the permutation-lock D, whereby, through a special action of the

55

permutation-lock, the time-movement may be disconnected or thrown out of engagement with the locking-lever E. These disconnecting devices I operate, as in the Kook and Hall

5 patents, by means of a second or special angle-bar, N, mounted in the permutation-lock and controlled by the same tumblers which are ordinarily used.

Referring now to the details of my disconnecting devices, K, Fig. 4, represents an angular lever mounted in the time-movement behind and concentric with the trigger F. At its lower end this lever K has a stud or finger, e, arranged to vibrate between and act against a stud, d, on the inner side of the time-trigger F, and a stud, e, on the inside of the latch or dog H, Fig. 1. This lever K is also provided with a horizontal arm, e', arranged to be depressed by a pin, f', on a vertical sliding plate, L, as shown in Figs. 2, 4, and 7, the latter connected by a bar, M, to the angle-bar N of the permutation-lock, the angle-bar and bar M having a slotted connection, as shown, to permit a limited independent play. The angle-bar N is operated, in the same manner as in the patent of Kook and Hall, by means of the ordinary lock-tumblers operated by the lock-spindle, a special and secret combination upon which to set up the tumblers being used.

30 Upon making use of the secret combination and operating the angle-bar N, it causes the bar M to draw down the plate L, which in turn, acting upon and turning the lever K, causes the lip e of the lever to act against the stud d of the trigger F, thereby throwing the latter out of engagement with the lock-bar E, leaving said lever free to fall and release the lock-bolts, when the combination-lock can be unlocked in the usual manner.

40 When the lever K is actuated from the combination-lock as above described, a hook, R, at its upper end, engages over a revolving shaft or spindle, S, of the time mechanism, in the same manner as in the patent to Flint, for 45 the purpose of holding the time mechanism momentarily in its disconnected condition. At the same time that the lever K throws the trigger F out of action it also acts upon the stud e of dog H, thereby preventing said dog from 50 engaging with the trigger F, thus leaving the latter free to engage again with the lever E as soon as the lever K is released by the rotation of the shaft S. The action of the lever K in holding the dog H out of action is a matter of 55 great importance, as the dog would otherwise engage with the trigger and hold the same in such position as to maintain the disconnection of the timer, and thus permit the safe to be unlocked by operating the combination-lock 60 while the time-movement is in motion. When, however, the dog H is held out of action by the lever K, as above described, the parts are left in such condition that the time-trigger F may immediately re-engage with the lever E 65 as soon as the hook R rises from the shaft of the timer. As in the patent to Flint, the hook

R retains the timer in a disconnected condition whenever the motion of the timer has ceased, but not otherwise, except for an instant, as above stated.

In order to unlock the safe when the timer has stopped, before disconnecting the trigger F, the secret combination is first made use of in the combination-lock to operate the angle-bar N and disconnect the timer, which is then 75 held out of action by the hook R. The ordinary combination of the lock is then set up by causing the tumblers, through the ordinary angle-bar, O, to retract the bolt of the lock from beneath the lever E, whereupon the front 80 end of the lever will fall, leaving the bolt-work of the safe free to move backward.

A serious danger encountered in the use of the disconnecting mechanism, operated by a second angle-bar, N, as in the Kook and Hall 85 patent, was found to exist in the fact that the notches or openings in the tumblers were brought into a straight line to operate each angle-bar. It was found that under this arrangement a person having knowledge of one 90 combination and ascertaining the difference between any given number of that combination and the corresponding number of the other combination could, by subtracting that difference from each of the numbers of the other 95 combination, determine exactly what that combination was. For example, it being discovered that the difference between the first number of the usual combination and the first number of the secret combination was ten, it 100 was only necessary to add or subtract ten from each of the numbers of the ordinary combination to ascertain exactly the secret combination. In order to overcome this difficulty I now construct either or both of the angle-bars 105 in such manner that the tumblers require to be brought into a different relation to each other in operating one bar from that which they occupy in operating the other bar. A simple method of accomplishing this result is 110 that of providing one of the angle-bars with screws or studs to enter the notches of the tumblers, said studs being placed out of line with each other. This construction is clearly 115 represented in Fig. 5, in which it will be seen that the angle-bar N is provided with screws a', arranged in different lines, the angle-bar being also provided, as an additional element of safety, with a series of holes to permit the position of the screws to be changed. As regards the construction of the angle-bars, the invention consists broadly in giving them such form that the disks or tumblers must occupy different relative positions to admit the respective bars. This peculiar construction of 120 the angle-bar N is the invention of J. L. Hall, to whom it was patented September 20, 1881, and therefore I make no claim to this device itself.

In practice it is found desirable to provide 130 the locks of the class herein described with two independent time-movements, so that the stop-

page of either one will not destroy the security of the lock. When the disconnecting mechanism is used in connection with two movements, it is necessary that the device for momentarily maintaining the disconnection of the movement from the lock shall be connected with both movements, and also that it shall be so arranged that the action of either movement shall re-establish the connection. To this end I make use of the arrangement represented in Fig. 7, in which K represents the disconnecting-lever, R the hook for holding the same out of action, and S the spindle upon which the hook engages, as in the figures previously described. T represents a shaft or spindle of the second time-movement, and U an elastic or spring hooked arm to engage therewith, this arm being secured at its lower end to the lever K, as shown. The hook R has its rear end extended behind the lever K in position to bear upon the spring-arm T. When the lever K is thrown forward by the disconnecting mechanism the hooked arms U and R engage over the respective shafts S and T, and if both shafts are at rest, the engagement will be a permanent one. If, however, either shaft be in motion, it will cause the corresponding hook to ride therefrom. If the hook R be disengaged from its shaft S, the arm K will fly backward against the hooked arm T and disengage it also; but if, on the other hand, the arm U be first disengaged, it will spring forward against the rear end of the hook R and cause its disengagement.

While it is preferred to retain the exact construction shown, it is manifest that the details of the two hooks may be modified, the essential feature of the invention in this regard consisting in the use of two hooks or detents being so arranged that either being unlocked first will release the other.

By thus combining and applying these several improvements or systems in one organized mechanism I produce a lock which combines the advantages of all of them, and which would seem to fulfill all the requisite of a complete safety device for safes, vaults, &c.

It is obvious that the invention may be applied to safe and vault doors which have other means of holding the bolt-work in a locked position, as well as those shown, it only being necessary to so modify the connections as to adapt the apparatus to the particular form or kind of device used to hold the bolt-work in its locked position, and which, as is well known, differs with different makers.

Having thus described my invention, what I claim is—

1. In a time locking mechanism, the com-

bination of a movable arm or trigger, F, arranged to hold the locking device in position, a dog, H, to hold said trigger out of the locking position until released by the time-movement, the lever K, and the connecting device L M, or equivalent means, arranged to be operated by a non-time lock, substantially as and for the purpose set forth. 60

2. In combination with a time-movement having an arm or trigger, F, arranged to hold the locking device in a locking position, a dog 70 to hold said trigger temporarily out of action, and the lever K, connected to the non-time lock and arranged on said trigger and dog, substantially as and for the purpose set forth.

3. In combination with a time-movement, the trigger F, provided with the stud d, the dog H, provided with the stud e, the lever K, with its hook R, arranged to engage upon a shaft of the time-movement and temporarily hold the trigger and its dog out of action, and the connecting device L M, arranged to be operated by the non-time lock, substantially as described. 75

4. In combination with a time-movement, the lever K, with its hook R, arranged to engage with one of the shafts of said time-movement, 85 and a connecting-bar, L M, or equivalent device, arranged to be operated by the non-time lock, substantially as described.

5. In a time-lock, the combination of two time-movements with two hooks, each arranged to engage with a shaft of its respective time-movement, a device substantially such as shown for causing said hooks to engage with said shafts by a positive motion, and means for locking the bolt-work, substantially as set forth. 90

6. In combination with a time locking mechanism, two hooks or devices, for holding the same out of action or disconnected from the dogging or locking devices, said hooks being 100 constructed to operate substantially as described, whereby the release of either of said hooks by its time-movement shall cause the release of the other hook, even though its time-movement may have stopped, as set forth. 105

7. In combination with a duplex time-movement, the arm or lever K, with its hook R, provided with an extension in rear of its pivot, and the spring-hook U, said parts being arranged to operate substantially as described, 110 whereby the release of either of said hooks will cause it to operate upon and release the other, as set forth.

BENJAMIN F. FLINT.
